(57) **CLAIM**

The ornamental design for a toilet tissue chest, as shown and described.

DESCRIPTION

FIG. 1 is a front elevational view of a toilet tissue chest showing our new design depicting a dowel to stow two rolls of toilet paper and a hinge and overlap on the top surface which allows the device to be mounted to a wall or the side of a countertop with a lip and allow access to the storage compartment;

FIG. 2 is a rear elevational view thereof;

FIG. 3 is a front view thereof;

FIG. 4 is a rear view thereof;

FIG. 5 is a top view thereof;

FIG. 6 is a bottom view thereof; and,

FIG. 7 is a side view thereof.
